UNITED STATES PATENT OFFICE.

MELVILLE W. CUNNINGHAM, OF CHICAGO, ILLINOIS.

DESIGN FOR AN ANIMAL FIGURE.

Application filed March 28, 1929. Serial No. 30,649. Term of patent 14 years.

To all whom it may concern:

Be it known that I, MELVILLE W. CUNNINGHAM, a citizen of the United States, residing at Chicago, in the county of Cook and State of Illinois, have invented a new, original, and ornamental Design for an Animal Figure, of which the following is a specification, reference being had to the accompanying drawing, forming part thereof.

The figure is a perspective view of an animal figure showing my new design.

I claim:

The ornamental design for an animal figure as shown.

MELVILLE W. CUNNINGHAM.
